UNITED STATES PATENT OFFICE.

MAURICE LEEN, OF CHICAGO, ILLINOIS.

SHIPPING CASE.

Application filed May 10, 1924. Serial No. 712,323.

To all whom it may concern:

Be it known that I, MAURICE LEEN, a citizen of the United States, residing at Chicago, in the county of Cook and State of Illinois, have invented new and useful Improvements in Shipping Cases, of which the following is a specification.

This invention relates to butter containers such as are used to ship the commodity from the creamery to the dealer, and its object is to provide a container of this kind which is peculiarly formed to lend the contents such shape as to fit them for cutting into carton-blocks or small squares for table use without loss or additional labor.

Another object of the invention is to provide a combined shipping and display case having novel means whereby a substantial portion of the butter may be exposed to facilitate the immediate removal of the contents, or part thereof, or for purposes of display.

A further and important object of the invention is to provide a combined shipping and display case wherein the upper and lower sections of the same are held in place by means of cleats which may be quickly removed when it is desired to expose the contents of the box and the box is so constructed that it may be used a number of times.

A further object of the invention is to provide a combined shipping and display case which is of highly simplified construction, durable in use and cheap to manufacture.

In the accompanying drawing forming a part of this application and in which like numerals are employed to designate like parts throughout the same,

Figure 1 is a perspective view illustrating the improved shipping and display case open to expose the contents of the same;

Fig. 2 is a vertical sectional view through the display case open to expose the contents, the case being mounted on a suitable stand;

Fig. 3 is a detail sectional view illustrating the connecting means for the upper and lower sections;

Fig. 4 is a perspective view of the combined shipping and display case closed.

In the drawing wherein for the purpose of illustration is shown a preferred embodiment of the invention, the numeral 5 designates a display stand having a horizontal top 6 and an inclined portion 7. The lower section 8 of the novel case is adapted to be

mounted on the inclined portion 7 while the upper sectional closure 9 is adapted to be mounted on the upper section 6.

The improved shipping and display case 60 consists principally of the upper and lower sections 9 and 8 respectively more or less similarly constructed and the top section may be provided with transverse reinforcing strips or members 10.

The side walls of the sections 8 and 9 are adapted to be arranged in edge to edge contact to enclose the contents 11 which may be butter, or the like. In preparing the container for shipment, the adapting strips 70 14 which are carried by the side and end walls of the top section 9 are extended into overlapping relation with the side and end walls of the lower section 8 so that lateral movement of the top section is prevented. Suitable cleats or straps 15 are secured to the lower section and to the lower portions of the straps 15 so as to securely and positively connect the strips 14 to the lower section. It is thus seen that the strips 14 not 80 only serve as a means for holding the upper section 9 against lateral and longitudinal movement on the lower section 8 but also serve as means for preventing the upward movement of the covered section. Furthermore the strips 14 substantially strengthen 85 and reinforce the container or case. The strips 14 are arranged midway of the corners of the case and if desired the fastening straps 15 may extend entirely across the bottom of the shipping case.

In use a quantity of butter or the like is placed in the lower compartment or section and the lid section 9 is then applied with the strips 14 in overlapping relation with 95 the side walls of the lower section. The cleats 15 are now secured in place so that the lid section cannot be accidentally displaced.

When it is desired to expose the contents 100 of the case it is merely necessary to break or remove the cleats 15 and then detach the cover section 9. When this is done half the contents of the case are exposed in the manner illustrated in Fig. 1.

A case constructed in accordance with this invention may be used a number of times as it is not necessary to mutilate or damage the same to gain access to the contents.

The peculiar advantage of the container 110 over the pails usually employed to ship butter, or over any other container in which

only the top of the contents is exposed, is that the butter is immediately removable in its entirety or in accurately divided parts; also, being in the form of a slab or prism, it occasions no waste, and requires no shaping or packing to adapt it for cutting by hand or machine into blocks for packing in cartons or prints, or into small squares for individual or table use. While the container 5 serves as a strong and compact shipping medium, its divisible feature at once exposes half of the contents for ready access and ease of removal. The device is thus a radical departure from the usual pail or crock, 10 in which the butter settles during shipment and can only be removed by the laborious scooping process, which also means waste or loss when cutting efficiency is considered. Needless to say, the producer will apply a 15 wax paper wrapper to each slab or prism of butter before depositing the same in its container as is usual in the packing of butter for purposes of sanitation.

Having thus described the invention, 20 what is claimed is:

1. A shipping case comprising upper and lower sections having side and end walls arranged in edge to edge contact, and strips carried by the side and end walls of one 25 of the sections and arranged in overlapping relation with the side and end walls of the other section; and means to rigidly connect

the overlapped portions of said strips to the adjacent sections whereby the two sections are securely and positively connected. 35

2. A shipping case comprising upper and lower sections having side and end walls arranged in edge to edge contact, and strips carried by the side and end walls of one of the sections and arranged in overlapping 40 relation with the side and end walls of the other section, means to rigidly connect the overlapped portions of said strips to the adjacent sections whereby the two sections are securely and positively connected, and 45 transversely extending reinforcing strips carried by one of the sections.

3. A shipping case comprising upper and lower sections having side and end walls arranged in edge to edge contact, and strips 50 carried by the side and end walls of one of the sections and arranged in overlapping relation with the side and end walls of the other section, means to rigidly connect the overlapped portions of said strips to the adjacent sections whereby the two sections are securely and positively connected, and 55 transversely extending reinforcing strips carried by one of the sections, the section provided with the strips being removable 60 to expose a portion of the contents of the other section.

In testimony whereof I affix my signature.
MAURICE LEEN.
